United States Patent Office.

CHARLES S. MURPHY AND DONALD McGREGOR, OF DETROIT, MICHIGAN.

Letters Patent No. 95,926, dated October 19, 1869.

IMPROVED SOAP-CUTTING MACHINE.

The Schedule referred to in these Letters Patent and making part of the same.

To whom it may concern:

Be it known that we, CHARLES S. MURPHY and DONALD McGREGOR, of Detroit, in the county of Wayne, and State of Michigan, have invented a new and useful Improvement in Soap-Cutting Apparatus; and we do declare that the following is a true and accurate description thereof, reference being had to the accompanying drawings, and to the letters of reference marked thereon, and being a part of this specification.

The object we have in this invention is to construct an apparatus, combined of several parts, for the purpose of cutting a mass of soap into slabs, then cutting the slabs into long bars, and then subdividing the long bars into short ones of equal length, thereby enabling the operators to perform the labor of reducing the mass to bars of any desired size and length with ease, and certainty in the uniformity of size in the bars.

The invention consists—

First, in the employment of a suitable vertical frame, across which are stretched, horizontally, a series of wires, drawn tight, and secured, in any convenient manner, at equal distances apart, the distances between the wires being the required thickness of the slabs; and the wires may be so attached to the frame that they may be adjusted to cut various thicknesses.

Second, in another frame, to one side and upon the top of which is secured a slotted bar, the distance between the slots being equal to the desired width of the bars to be cut, is another cutting-frame, provided with wires. The same machine may be supplied with several of these slotted bars, with varying distances between the slots, in order that bars of different widths may be cut when required, by substituting the different slotted bars in the machine. To the opposite side of this frame is pivoted another frame, to which are secured short cutting-wires, at equal distances apart, such distances corresponding with the distances between the slots in the slotted bar above referred to. These wires should also be so attached that they may be adjusted to cut various widths of bars.

Third, in a pair of slides, operating upon a table, to receive the bars after they are cut, and upon which they are carried to another table, which is provided with suitable guides for the purpose. In the passage of the slides from the one table to the other, there is placed another series of vertical wires, which should also be adjustable, by means of which the bars are subdivided into the desired lengths.

Fourth, in the novel and peculiar arrangement of the various parts of the apparatus for the purpose designed.

Having thus described the object of our invention, we will now proceed to describe its various parts, and the operation of the same, so that those skilled in the art can manufacture and operate the apparatus.

In the drawings—

A represents a vertical gallows-frame, which may be secured to the floor in any convenient method.

Between the two upright posts of this frame are stretched the cutting-wires *a*, at equal distances apart, and adjustable so as to cut any required thickness, as hereinbefore described.

Also, secured to the floor, and extending under the frame, as shown, are the ways *B*, upon which the mass of soap to be cut is moved forward to the cutting-wires and through the frame.

C is another frame, to the top of one side of which is secured the slotted bar *b*, the slots, or cuts into said bar being vertical, from the top, at equal distances apart, to correspond with the width of the bar into which it is desired to cut the soap.

Pivoted to the opposite side of the frame *C*, at *c*, is the vibrating frame *D*, to the cross-bars *d* and *e* of which are secured the cutting-wires *e*, at equal distances apart, to correspond with the distances between the slots, or cuts in the slotted bar *b*. These wires should be so arranged and secured as to be adjustable in any convenient way, so that bars of different widths can be cut when desired.

Secured to, and vibrating with this frame *D*, there is a table, *E*, which is provided with two guides, *f*, which guide the slides *F*, in their movements, and which are coincident, when the corner *g* of the vibrating table *E* is brought into line with the corner *h* of the stationary table *G*, with similar guides *i* secured to the top of said stationary table *G*.

H is a post, secured to the frame *D*, and supports a proper sheave-block, over which passes the cord *j*, one end of which is secured to the frame *D*, and the other to the counterbalance-weight *I*, to assist in vibrating or semi-rotating the said frame *D*.

The cross-bar *d* of the frame *D* is provided with a projection, *K*, for the purpose hereinafter explained.

To the stationary table *G* is secured the gallows-frame *K*, between the cross-piece *l* of which and the bed of the table is secured the vertical wires *m*, which should be secured so as to secure an adjustability, so that they may be used for cutting different lengths.

The outside wires are designed to trim off the ends of the bars, while the intermediate wire or wires will subdivide the bar into suitable and equal lengths.

The operation of this machine is as follows:

The mass of soap, being ready for cutting, is slid up on to the ways *B*, at the rear end thereof, and driven forward against the cutting-wires *a*, and in the continued forward motion of the mass, the wires pass through the mass, cutting it into slabs of any required thickness.

After this is done, the mass, cut into slabs, as described, is left standing upon the front end of the ways, opposite the frame *C*.

At this time, the plane of the table *E* should be

coincident with the plane of the stationary table G. Then a slab is removed from the mass, and one edge thereof rested upon the upper edge of the slotted bar b, and its opposite edge placed upon the projection k of the bar d.

Then, by means of the handle L, the frame D is vibrated toward the slab, the upper edge of which is presented to the cutting-wires o, which, in the deflection of the frame, pass through the slab, thereby cutting into bars of a uniform width.

The bars will then be found resting upon the slides F, and by raising the frame until the corners g and h are in contact, as hereinbefore described, the slides may be pushed, under the gallows-frame K, on to the table G, the cutting-wires m cutting the bars resting upon the slides into equal lengths, and trimming their ends.

We are aware that a frame similar to the frame A, and provided with cutting-wires a, has been in use. We do not claim that, except in combination with the other parts of our apparatus.

What we claim as our invention, and desire to secure by Letters Patent, is—

1. The vibrating frame D, provided with cutting-wires o, table E, and handle L, in combination with the frame C, when constructed and operating substantially as herein specified.

2. In combination with the above-named parts, the slides F, table G, and cutting-wires m, when arranged relatively to each other, and operating as herein set forth.

3. In combination with the frames C, D, and G, provided with the various parts herein mentioned, the frame A, provided with cutting-wires a, and the ways B, when constructed, combined, and operating substantially as and for the purposes herein described.

CHAS. S. MURPHY.
DONALD McGREGOR.
